UNITED STATES PATENT OFFICE

2,337,485

COATED RADIATION EMITTING BULB

George H. Meridith, Cleveland, Ohio, assignor to
General Electric Company, a corporation of
New York

Application March 1, 1943, Serial No. 477,671

9 Claims.

(Cl. 67—31)

My invention relates, in general, to electric lamps and similar devices for the production of invisible radiations, such as infrared or ultraviolet radiations, and to the manufacture of such devices. More particularly, my invention relates to means for rendering the glass envelope or bulb of such devices impervious to visible radiations while permitting the transmission therethrough of invisible radiations such as infrared or ultraviolet rays.

It has been known heretofore to coat the glass bulbs of photoflash lamps, such as are used for photographic purposes, with a layer of an infrared or ultraviolet transmitting lacquer capable of absorbing and blocking out any and all visible radiations generated within the bulb. Such flash lamps are especially suitable for so-called "black-out" photography. The usual procedure, in applying such a lacquer coating to the bulb, is to simply immerse the lamp bulb in a bath of the lacquer material and to then introduce the coated lamps into an oven or drying chamber where the lamps are heated to dry the lacquer coating on the bulbs. With such procedure, however, it has been found that for some reason or other, numerous air or gas bubbles are formed in the lacquer coating immediately adjacent the junction between the lamp base and bulb. It may be that such bubbles result from the presence of trapped air within the annular space between the base shell and the bulb. Such a bubble formation permits the passage of visible radiations therethrough so that the lamp is not completely light-tight. Moreover, on drying, the lacquer coating bridging the gap between the lamp bulb and the rim of the base shell stretches thin to such a degree as to permit the transmission of visible radiations therethrough.

It is an object of the present invention to overcome the above-mentioned defects and provide a lamp the bulb of which is positively light-tight. Another object of my invention is to provide a photoflash lamp which will emit a flash of actinic radiation solely within the infrared region of the spectrum.

Further objects and advantages of my invention will appear from the following description of a species thereof and from the accompanying drawing, in which:

Fig. 1 is an elevation, partly in section, of a lamp comprising my invention; Fig. 2 is a fragmentary section, on an enlarged scale, of the base and the adjacent neck portion of the bulb of the lamp shown in Fig. 1; Fig. 3 is a fragmentary view, partly in elevation and partly in section,

of the lamp shown in Fig. 1 at an intermediate stage in its manufacture, the section being taken at the side soldered connection; and Fig. 4 is a view, similar to Fig. 2, showing the lamp comprising my invention at a later stage in its manufacture.

Referring to the drawing, the invention is there shown in connection with a photoflash lamp of a well-known type used for photographic purposes. The lamp comprises a glass bulb 10 having a neck portion 11 to which a base 12 is attached by a ring or layer of basing cement 13 (Fig. 2). The said base comprises a metal shell portion 14 provided at one end thereof with a bottom or center contact eyelet 15 fastened to the shell 14 by a button 16 of insulating material, such as glass. The other or open end of the base shell 14 surrounds the neck 11 of the bulb 10 and is secured thereto by the basing cement 13 which is disposed in the annular space between the bulb neck and the surrounding portion of the base shell. The basing cement 13 may comprise a mixture of a synthetic resin such as Bakelite, rosin, a filler such as marble flour, a binding agent such as shellac, and alcohol.

The bulb 10 is provided with a re-entrant stem 17 extending inwardly from the neck end of the bulb and having a pair of leading-in wires 18, 19 sealed therein and extending therethrough. The outer ends of the said leading-in wires 18, 19 are connected to the metal shell 14 and the bottom contact eyelet 15, respectively, of the lamp base 12, the wire 18 being bent back over the rim 20 of the base shell, through a notch 26 (Fig. 3) in the said rim, and soldered to the exterior surface of the shell while the other wire 19 extends through the eyelet 15 and is soldered thereto. Most of the bubbles referred to hereinabove form in the lacquer bulb coating adjacent the soldered connection at the notch 26.

Disposed within the bulb 10 is an ignition filament 21 which is connected to and supported by the inner portions of the leading-in wires 18, 19. The inner ends of the said leading-in wires and the adjacent portions of the filament 21 are coated with a layer of a suitable fulminating substance or primer 22.

The bulb 10 may be filled with a quantity of readily combustible flash material 23 loosely arranged in the bulb within effective ignition range of the ignition filament 21 therein. The combustible material 23 may consist of the well-known leaf foil, wire or shredded foil of aluminum and/or magnesium, or alloys thereof. The bulb 10 also contains a filling of oxygen or oxygen-

containing gas at a suitable pressure for supporting the combustion of the combustible material 23. The pressure of this gaseous filling will vary between about 180 and 600 mm., depending upon the type of gas employed, the size of the bulb, and the quantity and type of combustible material therein.

When an electric current is passed through the filament 21, the heating of the filament by such current immediately ignites the primer 22 which in turn ignites the combustible material 23. The ensuing combustion of the combustible material 23 then produces a flash of actinic light of relatively high intensity. The light so generated is composed of radiations within both the visible and invisible (infrared and ultraviolet) regions of the spectrum.

In accordance with the invention, the bulb 10 is provided with a filter in the form of a coating 24 on the bulb for absorbing all the visible radiations generated within the bulb while freely transmitting all, or at least a portion of, the invisible radiations. The said coating 24 consists of a suitable material, such as a lacquer, which is capable of effectively absorbing all the visible radiations and freely transmitting all or part of the invisible radiations such as the infrared and/or ultraviolet rays. For infrared transmitting purposes, I have found the material commercially known as Eastman No. 20714 infrared transmitting lacquer, manufactured and sold by the Eastman Kodak Company of Rochester, New York, to be particularly suitable.

The coating 24 of light-absorbing lacquer is applied to the lamp 10 by immersing the lamp, base up, in a bath of the lacquer material so that the entire exposed portion of the bulb 10, as well as the base shell 14 for a short distance from the rim 20 thereof, are submerged in the lacquer so as to form a coating over the entire exposed outer surface of the bulb and the rim portions of the base shell. The lamp is then removed from the bath of lacquer material and placed in a drying oven where the lamp is heated at a temperature of the order of 50° C. to dry the lacquer coating 24 on the bulb. The above coating operation may be repeated, if desired, so as to provide a double coating of the light-absorbing material on the bulb.

In accordance with the invention, I have found that, whatever their cause, the formation of light-transmitting bubbles and thin spots in the lacquer coating 24 at the junction of the base shell 14 and bulb 10 such as would normally allow transmission of visible radiations, is prevented by the application of an intermediate layer or fillet 25 of suitable filler material to the said junction between the bulb and base prior to the application of the light-absorbing coating 24 to the bulb. The said filler material 25 completely fills any annular space remaining between the bulb 10 and the rim portions of the base shell 14 and, in addition, fills the "corner" between the bulb and the rim 20 (as shown in Fig. 4) so as to present a smooth continuous surface for the lacquer coating 24 to ride up as the lamp is immersed in the lacquer coating bath. As a result, there are no pockets or crevices at the junction between the base shell 14 and the bulb 10 within which air could be trapped, during the immersion of the lamp in the lacquer coating 24 at the said junction. Moreover, the filling of the corner between the bulb 10 and the rim 20

of the base shell 14 eliminates, or greatly minimizes, the stretching and thinning out of the lacquer coating 24 at the junction between the bulb and the base shell such as would normally permit transmission to some degree of the visible radiations generated within the bulb. As shown in Fig. 4, the filler material 25 preferably overlaps or extends down onto the outer surface of the base shell 14 for a short distance, such as $\frac{1}{16}$ of an inch or thereabouts, so as to assure the complete filling up of the corner between the bulb and the rim 20 of the base shell and produce a fillet the outer surface of which merges into the outer surfaces of the bulb 10 and base shell 14 so as to form one continuous and uninterrupted surface therewith.

The fillet 25 is made of a material, such as a natural or synthetic resin, shellac, lacquer, or other resinous material, which will readily fill up the space and the corner between the bulb 10 and the rim 20 of the base shell 14 and which is sufficiently plastic so as not to crack on drying. A high-viscosity shellac composition, however, is preferably employed as the filler material 25. A suitable dark-colored material, such as a dark blue or black dye or pigment, is preferably added to the filler material 25 so as to render the filler material itself light-absorbing and thus further insure the complete absorption of all visible radiations at and adjacent the junction of the base shell with the bulb.

The filler material 25 may be applied to the lamp in any suitable manner, such as by painting it on with a small brush. Preferably, however, the filler material 25 is deposited on the lamp by a thin metal disc or roller which rotates through a pool of the shellac or lacquer filler material and with which the lamp is held in rolling contact, the lamp being held in a freely rotatable holder and being pressed into engagement with the flat peripheral edge of the rotating disc in such a way that the said peripheral edge contacts the lamp at the junction between the base shell and the bulb.

Following the application of the filler material 25 to the lamp, it is allowed to dry thereon after which the light-absorbing coating 24 is applied to the lamp bulb in the manner set forth hereinbefore.

While I have described the invention as applied to a photoflash lamp, it is obvious that the invention is applicable in all cases where it is desired to render the bulb of a lamp or similar radiation-emitting device (of the type comprising a bulb having a base attached thereto and radiant energy-producing means within the bulb) selectively transparent to certain only of the radiations generated by said radiant energy-producing means through the use of a radiation-absorbing coating on the exposed surface of the bulb.

What I claim as new and desire to secure by Letters Patent of the United States is:

1. A radiation-emitting device comprising a bulb, radiant energy-producing means within said bulb, a base secured to said bulb and substantially abutting against the wall of said bulb, a quantity of filler material disposed at and adjacent to the junction between the base and bulb wall to form a fillet therebetween, and a coating of radiation-absorbing material on the exposed surface of said bulb and on said fillet, said coating being selectively transparent to certain only of the radiations generated within said bulb by said radiant energy-producing means.

2. A radiation-emitting device comprising a bulb, radiant energy-producing means within said bulb, a base secured to said bulb and substantially abutting against the wall of said bulb, a quantity of filler material disposed at and adjacent to the junction between the base and bulb wall to form a fillet therebetween, and a coating of radiation-absorbing material on the exposed surface of said bulb and on said fillet, said coating being impervious to the visible radiations, but permeable to at least certain of the invisible radiations, generated within said bulb by said radiant energy-producing means.

3. A radiation-emitting device comprising a bulb, radiant energy-producing means within said bulb, a base secured to said bulb and substantially abutting against the wall of said bulb, a quantity of filler material disposed at and adjacent to the junction between the base and bulb wall to form a fillet therebetween, and a coating of radiation-absorbing material on the exposed surface of said bulb and on said fillet, said coating being impervious to the visible radiations, but permeable to infrared radiations, generated within said bulb by said radiant energy-producing means.

4. A flash lamp comprising a bulb, actinic light-producing means within said bulb, a base secured to said bulb and substantially abutting against the wall of said bulb, a quantity of filler material disposed at and adjacent to the junction between the base and bulb wall to form a fillet therebetween, and a coating of radiation-absorbing material on the exposed surface of said bulb and on said fillet, said coating being selectively transparent to certain only of the radiations generated within said bulb by said light-producing means.

5. A flash lamp comprising a bulb, actinic light-producing means within said bulb, a base secured to said bulb and substantially abutting against the wall of said bulb, a quantity of filler material disposed at and adjacent to the junction between the base and bulb wall to form a fillet therebetween, and a coating of radiation-absorbing material on the exposed surface of said bulb and on said fillet, said coating being impervious to the visible radiations, but permeable to at least certain of the invisible radiations, generated within said bulb by said light-producing means.

6. A flash lamp comprising a bulb, actinic light-producing means within said bulb, a base secured to said bulb and substantially abutting against the wall of said bulb, a quantity of filler material

10 disposed at and adjacent to the junction between the base and bulb wall to form a fillet therebetween, and a coating of radiation-absorbing material on the exposed surface of said bulb and on said fillet, said coating being completely impervious to the visible radiations, but permeable to infrared radiations, generated within said bulb by said light-producing means whereby said flash lamp emits solely infrared radiations when flashed.

15 7. A flash lamp comprising a bulb, actinic light-producing means within said bulb, a base secured to said bulb and substantially abutting against the wall of said bulb, a quantity of resinous material disposed at and adjacent to the junction between the base and bulb wall to form a fillet therebetween the outer surface of which forms one continuous and uninterrupted surface with the outer surfaces of said base and bulb wall, and a coating of radiation-absorbing material on the exposed outer surface of said bulb and on said fillet, said coating being completely impervious to the visible radiations, but permeable to infrared radiations, generated within said bulb by said light-producing means whereby said flash lamp emits solely infrared radiations when flashed.

20 8. A flash lamp comprising a bulb, actinic light-producing means within said bulb, a base secured to said bulb and substantially abutting against the wall of said bulb, a quantity of filler material comprising a shellac composition containing a dark-colored light-absorbing agent disposed at and adjacent to the junction between the base and bulb wall to form a fillet therebetween the outer surface of which forms one continuous and uninterrupted surface with the outer surfaces of said base and bulb wall, and a coating of radiation-absorbing material on the exposed outer surface of said bulb and on said fillet, said coating being completely impervious to the visible radiations, but permeable to infrared radiations, generated within said bulb by said light-producing means whereby said flash lamp emits solely infrared radiations when flashed.

25 9. The method of rendering completely light-tight the bulb of an electric device having a base abutting against the wall of said bulb, which method consists in first applying a quantity of filler material to the junction between the base and bulb wall to form a fillet therebetween, immersing said device, base up, in a bath of light-absorbing material to form a coating on the exposed surface of said bulb and on said fillet, and then drying said coating.

40 45 50 GEORGE H. MERIDITH.
